Primary Examiner — Garth Rademaker*Assistant Examiner* — Samantha Q Lawrence(74) *Attorney, Agent, or Firm* — Nixon & Vanderhye, PC(57) **CLAIM**

The ornamental design for a building, as shown and described.

DESCRIPTION

FIG. 1 is a top plan view of a building;

FIG. 2 is a rear elevational view thereof;

FIG. 3 is a front elevational view thereof;

FIG. 4 is a left elevational view thereof; and,

FIG. 5 is a right elevational view thereof.

The broken lines in the figures depict portions of the building which form no part of the claimed design.
